BALLOON CATHETER HAVING AN INTEGRAL SELF-SEALING INFLATION VALVE

Reinold E. Swanson, Rehoboth, Mass., assignor to Davol Inc., a corporation of Rhode Island
Filed Apr. 1, 1965, Ser. No. 444,867
7 Claims. (Cl. 128—349)

ABSTRACT OF THE DISCLOSURE

A self-sealing valve for catheters and the like having means for securing said valve within and adjacent the open end of the inflating lumen of the catheter, said valve having means permitting fluid flow into the catheter through said inflating lumen, said means automatically preventing backflow of the fluid from the catheter, thus maintaining the catheter inflated.

A primary object of this invention is the provision of a valve adapted to be integrated with an inflating tube, such as the inflating lumen of a catheter, said valve permitting the flow of fluid under pressure inwardly through said lumen, and at the same time normally preventing the flow of fluid outwardly through said lumen.

A primary object of this invention is the provision of novel and improved means for integrating a self-sealing or one-way valve with the proximal end of an inflating lumen of the type normally found in catheters and the like.

Another important object is the provision of a novel and improved self-sealing or one-way valve per se, the construction of said valve being such that it readily lends itself to manufacture and assembly on an extremely economical basis.

A further object is the provision of a self-sealing valve which may be easily and effectively integrated with the proximal end of the inflating lumen of catheters and the like, and which, although economically feasible to manufacture and assemble, is nevertheless highly effective and durable in use.

Other objects, features and advantages of the invention will become apparent as the description thereof proceeds when considered in connection with the accompanying illustrative drawings.

In the drawings which illustrate the best mode presently contemplated for carrying out the present invention:

FIG. 1 is a front elevational view of a catheter having a self-sealing valve integrated therewith in accordance with the instant invention;

FIG. 2 is a view similar to FIG. 1, mostly in section;

FIG. 3 is a section, on an enlarged scale, taken on line 3—3 of FIG. 2, showing the valve in open position;

FIG. 4 is a view similar to FIG. 3 showing the valve in closed position;

FIG. 5 is an elevational view, partly in section, showing the valve housing per se;

FIG. 6 is a top plan view of the housing shown in FIG. 5;

FIG. 7 is a bottom plan view of the housing shown in FIG. 5; and

FIG. 8 is a perspective view of the valve member per se which forms a part of the instant invention.

Referring to the drawings, a conventional catheter is shown generally at 10 having a self-sealing valve shown generally at 12 integrated therewith. As stated, the catheter 10 is of completely conventional construction and comprises an elongated flexible shaft 14 of any suitable material, such as rubber or plastic, having drainage eyes 16 located adjacent the distal end 18 of the catheter. A

2

drainage lumen 20 extends longitudinally through the catheter shaft and communicates with eyes 16. Drainage lumen 20 is provided with an enlarged proximal portion 22 which in use is adapted to interconnect with a suitable drainage tube (not shown) as is well known in the art. The shaft 14 further comprises an inflating lumen 24 which also extends longitudinally through the catheter shaft in side-by-side relation with drainage lumen 20. The inflating lumen 24 terminates at its distal end in an opening 26 formed in the catheter wall, said opening permitting communication between the inflating lumen and an inflatable sac 28 secured to the exterior of the catheter, adjacent the distal end thereof, but spaced inwardly from the eyes 16. At its proximal end, inflating lumen 24 separates from the catheter shaft 14 as at 30 to facilitate the introduction of pressurized fluid to the inflating lumen. It will be obvious that the introduction of pressurized fluid into and through inflating lumen 24 will cause the sac 28 to distend until the sac becomes inflated, as shown in broken lines in FIG. 2. It will be understood that when a patient is catheterized, the sac 28 is inflated for retention and/or pressure purposes.

The conventional technique for inflating the sac 28 is to introduce a syringe to the proximal end of inflating lumen 14, and by use of the syringe to force air or other fluid through inflating lumen 24 until the sac 28 is inflated. Once the sac has been inflated, the syringe is removed, and it then becomes necessary to provide means for maintaining the sac inflated. This has been done by a variety of ways, such as by providing a physical clamp that pinches the portion 30 of inflating lumen 24 to block fluid flow therethrough. This technique has sometimes proven undesirable since it first of all is necessary that such a clamp be available, and, secondly, it is sometimes difficult to apply the clamp without losing some of the pressure from the inflated sac. Also, even when the portion 30 is so clamped, there is always danger that the clamp is not a completely secure one and that the sac will slowly deflate. Another often-used technique has been to block the proximal end of the inflating lumen with a rubber plug which must then be punctured by a hypodermic needle provided on the syringe, the plug being self-sealing when the needle and syringe are withdrawn. This technique likewise has disadvantages in that it requires use of a very fine needle and, further, in that the operator may inadvertently puncture the wall of the inflating lumen and/or his own fingers. These disadvantages have been overcome by the use of the integrated, self-sealing valve illustrated generally at 12, the details of which will now be described.

The valve 12 actually comprises three separate parts, i.e., a housing 32 (FIG. 5), a valve member 34 (FIG. 8), and a plug 36 (FIGS. 3 and 4). All of these parts may be made of any suitable nontoxic material, although in accordance with the instant invention it is preferred to injection mold each of these three parts using a material such as Delrin.

Referring now to FIGS. 5 through 7, it will be seen that housing 32 is of cylindrical configuration and has a bore 38 extending longitudinally therethrough. Adjacent its upper end, the bore 38 is provided with an annular beveled shoulder 40 which defines and communicates with a reduced bore portion 42. Adjacent the opposite end of bore 38 there is provided an annular inwardly extending rib 44, the purpose of which will hereinafter become apparent. The cylindrical side wall 46 of housing 32 has an open-ended annular channel 48 formed therein, it being noted that the open end of said channel is adjacent the rib 44. It will further be noted that the free edge of the outer wall of said channel is beveled as at 50.

Referring now to FIGS. 3, 4 and 8, it will be seen that

valve member 34 comprises a cylindrical body 52, beveled at its end edges as at 54 and having outwardly projecting ribs 56 extending in a diametric direction across the end surfaces 58 of body 52. The valve member 34 is preferably perfectly symmetrical.

The diameter of cylindrical body 52 is such that the valve member 34 is freely slidable in bore 38 of housing 32, there being sufficient clearance between the wall defining said bore and the cylindrical body 52 to permit free flow of fluid through the bore 38. However, the diameter of cylindrical body 52 is larger than that of reduced bore portion 42, whereupon when valve member 34 is forced against shoulder 40, as illustrated in FIG. 4, the said valve member will effectively seal the opening 42 so as to block and prevent the flow of fluid therethrough. In this position, the beveled surfaces 54 and 40 cooperate to center the valve member 34 and at the same time provide an effective valve seat therefor, in a manner well known in the valve art. It is important to note that the length of the ribs 56 is less than the diameter of reduced bore portion 42, since otherwise the valve member would not be able to move to its closed position, as illustrated in FIG. 4. It will be understood that the valve member 34 is mounted in bore 38 before the housing 32 is integrated with the inflating lumen 24. The assembly of valve member 34 in bore 38 is achieved simply by forcing the valve member upwardly into the bore past the annular rib 44, it being understood that the flexibility of the wall from which rib 44 extends will be sufficient to enable the valve member to easily be forced past the rib 44. Since the valve member 34 is perfectly symmetrical, the aforescribed assembly of the valve member and housing 32 is facilitated, since care need not be taken to orient any particular end of valve member 34 with any particular end of bore 38.

Once the valve member 34 has been assembled in the manner above described, the plug 36 is introduced to maintain the valve member captured within housing 32. Plug 36 is of generally cylindrical configuration and is designed so as to be a press fit within the lower end of housing 32. An annular groove 60 is provided on plug 36, it being understood that the groove 60 will snap-receive the aforescribed rib 44 to lock the plug in assembled relation. A bore 62 extends through plug 36, and, in effect, plug 36 and its bore 62 actually comprise a second reduced bore portion for the bore 38. It is important to note that the diameter of bore 62 is less than the length of the ribs 56, whereupon if valve member 34 is forced downwardly against plug 36, the rib 56 will bridge the bore 62 to prevent the cylindrical body 52 from engaging said bore so as to seal or block same.

Once the housing 32, valve member 34 and plug 36 have been assembled in the aforescribed manner, the valve 12 is ready for securement to the catheter 10. This securement is accomplished by sliding the proximal end portion 30 of lumen 24 into the channel 48, as clearly illustrated in FIGS. 3 and 4. As soon as the proximal end of the inflating lumen has been slid into the channel, it may be maintained therein by any suitable means, although in accordance with the instant invention it is preferred to effect this integration of the parts by crimping the beveled edge 50 of housing 32 inwardly as at 64 so as to securely grip or clamp the tubular wall of the lumen between the inner and outer walls of channel 48. Beveled edge 50 facilitates this crimping operation since it provides a relatively sharp edge that will bite into and better grip the lumen wall.

In operation and use, when it is desired to inflate the sac 28, a syringe 66 (having no needle at its tip) is inserted through reduced bore 42, as illustrated in FIG. 3. Since the length of rib 56 is just slightly less than the diameter of reduced bore portion 42, it follows that the inner diameter of the tip portion of syringe 66 is less than the length of rib 56, whereupon the rib bridges the tip of the syringe to insure that the syringe tip can

never engage and abut against body portion 52, since if this were possible the body 52 would block flow of pressurized fluid from the syringe. Since entry of the syringe 66 through reduced bore portion 42 dislodges the valve member 34 from the position illustrated in FIG. 4 to the position illustrated in FIG. 3, and since the tip of the syringe is maintained in spaced relation from body portion 52 by virtue of rib 56, it follows that air or fluid under pressure may be forced through bore 38 (passing around the outer periphery of cylindrical body 52), the pressurized fluid then passing through bore 62 to lumen 24 and then eventually to sac 28 in order to inflate same. As soon as the sac is sufficiently inflated, the syringe is removed, whereupon back pressure will automatically move the valve member 34 to the closed position illustrated in FIG. 4, thus creating a seal which maintains the sac 28 inflated. If the syringe 66 is inadvertently pushed in too far, no harm can be done since the lower rib 56 will prevent the bottom of cylindrical body 52 from sealing the opening 62. When it is desired to deflate the sac 28, it is simply necessary to introduce a pin of some sort (not shown) through reduced bore portion 42 into engagement with valve member 34, whereupon as the valve member is depressed, the seal will be broken and the sac will commence to deflate.

It will thus be seen that unique and effective means have been provided for integrating a self-sealing or one-way valve with the inflating lumen of a catheter. Although the valve 12 has been shown and described in combination with the inflating lumen of the catheter, it will be understood that this valve is actually usable with and applicable to any type of inflating tube, whether associated with a catheter or not.

While there is shown and described herein certain specific structure embodying the invention, it will be manifest to those skilled in the art that various modifications and rearrangements of the parts may be made without departing from the spirit and scope of the underlying inventive concept and that the same is not limited to the particular forms herein shown and described except insofar as indicated by the scope of the appended claims.

What is claimed is:

1. In combination, a catheter having a tubular inflating lumen at the proximal end thereof, a one-way valve permanently secured to the proximal end of said inflating lumen, said valve having means permitting fluid under pressure to flow into said lumen but normally preventing fluid under pressure from flowing out through said lumen, said valve comprising a hollow cylindrical housing, the cylindrical wall of said housing having an open-ended annular channel formed therein, said channel receiving therein the proximal end of said inflating lumen and means maintaining said inflating lumen in said channel.

2. The combination of claim 1 further characterized in that said last-mentioned means comprise an inward deflection of the free edge of the outer wall defining said channel, whereby to clamp said inflating lumen within said channel.

3. A self-sealing valve for catheters and the like comprising a cylindrical housing having a bore extending therethrough, annular means at opposite ends of said housing restricting said bore at its opposite ends to define a first reduced portion at one end of said bore and a second reduced portion at the other end thereof, a solid, cylindrical, symmetrical valve member slidably mounted in said bore and having sufficient clearance from the surface defining said bore as to freely permit fluid flow through said housing, an outstanding rib extending across each end surface of said valve member, the diameter of said valve member being greater than that of either reduced portion and the length of said ribs being less than the diameter of said first reduced portion and greater than that of said second reduced portion whereby when said member is forced toward said one end of said housing, the adjacent said rib will extend into said first reduced

portion and said member will seal off said first reduced portion to block fluid flow through said housing, but when said valve member is forced against the said other end of said housing, the adjacent said rib will bridge said second reduced portion to prevent said member from acting as a seal.

4. The valve of claim 3 further characterized in that the said annular means that define the said second reduced portion is a plug having an opening extending therethrough, said plug being secured within said bore at the said other end of said housing.

5. A self-sealing valve for catheters and the like comprising a cylindrical housing having a bore extending therethrough, a first reduced portion at one end of said bore and a second reduced portion at the other end thereof, said second reduced portion being defined by a plug having an opening extending therethrough, which plug is secured with said bore at said other end, a cylindrical, symmetrical valve member slidably mounted in said bore and having sufficient clearance from the surface defining said bore as to freely permit fluid flow through said housing, an outstanding rib extending across each end surface of said valve member, the diameter of said valve member being greater than that of either reduced portion and the length of said ribs being less than the diameter of said first reduced portion and greater than that of said second reduced portion, whereby when said member is forced toward said one end of said housing, the adjacent said rib will extend into said first reduced portion and said member will seal off said first reduced portion to block fluid flow through said housing, but when said valve member is forced against the said other end of said housing, the adjacent said rib will bridge said second reduced portion to prevent said member from acting as a seal, said housing being of integral, one-piece construction, the cylindrical wall of said housing having an open-ended annular channel formed therein, the open end of said channel being located at said other end of said housing.

6. In combination, a catheter having a tubular inflating lumen at the proximal end thereof, a self-sealing valve

for catheters and the like comprising a cylindrical housing having a bore extending therethrough, a first reduced portion at one end of said bore and a second reduced portion at the other end thereof, a cylindrical and symmetrical valve member slidably mounted in said bore and having sufficient clearance from the surface defining said bore as to freely permit fluid flow through said housing, an outstanding rib extending across each end surface of said valve member, the diameter of said valve member being greater than that of either reduced portion and the length of said ribs being less than the diameter of said first reduced portion and greater than that of said second reduced portion, whereby when said member is forced toward said one end of said housing, the adjacent said rib will extend into said first reduced portion and said member will seal off said first reduced portion to block fluid flow through said housing, but when said valve member is forced against the said other end of said housing, the adjacent said rib will bridge said second reduced portion to prevent said member from acting as a seal, and means for securing said valve to said inflating lumen, said securing means comprising an annular open-ended channel in the cylindrical wall of said housing, said channel open end being located at said other end of said housing, said channel slidably receiving the free end of said inflating lumen therein, and means maintaining said inflating lumen in said channel.

7. The combination of claim 6 further characterized in that said last-mentioned means comprise an inward deflection of the free edge of the outer wall defining said channel, whereby to clamp said inflating lumen within said channel.
